UNITED STATES PATENT OFFICE.

GEORGE W. SMITH, JR., OF PITTSBURGH, PENNSYLVANIA.

WRINGER-ROLL GUARD.

Application filed December 1, 1926. Serial No. 151,898.

This invention relates to an improvement in clothes wringers, more particularly to a combined wringer roll guard and stripper.

It is among the objects of the invention to provide an attachment for wringer rolls having the combined function of a guard and roll stripper and which shall be adapted for use on any clothes wringer without modifying the wringer structure and which shall require no alterations or special appliances in the wringer per se for its application and use.

Another object of the invention is to provide a wringer roll guard and stripper of the above designated character which shall be in the nature of an appliance designed to constitute an independent element that may be readily placed on the roll or removed therefrom without requiring it to be attached or in any manner supported on the wringer frame.

Another object of the invention is to provide a wringer roll guard of simple mechanical construction which shall be relatively inexpensive to manufacture and which shall function to prevent the adherence of clothing to the wringer roll whereby possibility of injury to the fabric and breakage of the wringer mechanism becomes very remote.

Heretofore various provisions have been made to provide guards and strippers for wringer rolls to prevent injury to the person feeding clothing therebetween, and to prevent the clothing from clinging or adhering to the rolls whereby they are wrapped around one of the cooperating roll members.

Guards and strippers as heretofore constructed are in the form of sheet metal members of arcuate shape which are adapted to be attached to the wringer frame in some manner to secure them in the proper position to cooperate with the wringer rolls. The prior art devices were either complicated in their structure which enhanced their cost of manufacture or they were required to be built into the wringer frames or fastened with special brackets which restricted their use.

In accordance with the present invention the wringer guard and roll stripper is constituted a self-contained member which is mounted in proper cooperative relation with the wringer rolls by simply placing the guard thereon. The guard is formed of sheet metal to constitute a yielding structure which is provided with a plurality of rolls

that are adapted to cooperate with the surface of the wringer rolls to maintain the guard in its proper operating position. The construction of the guard is such as to permit placing it on the rolls or removing it therefrom at the will of the operator without the need of tools or skill.

In the accompanying drawing constituting a part hereof and in which like reference characters designate like parts, Fig. 1 is a view in perspective of a clothes wringer having a portion of one of the frame members broken away which embodies the principle of this invention; Fig. 2 a diagrammatic view illustrating the position and cooperative relation of a pair of wringer rolls and a wringer guard and stripper in accordance with the present invention; Fig. 3 a similar view illustrating a modified form of guard and stripper; and Fig. 4 illustrates still another modified form of the invention.

Referring to the several figures of the drawing, the structure therein illustrated comprises a wringer frame 1, having vertical side frame portions 2 provided with fixed journal bearings 3. The side frames 2 are further provided with slotted openings 4 for receiving movable journal bearing blocks 5. The stationary and movable journal bearings 3 and 5 are adapted to receive the journals 6 and 7 of a pair of cooperating wringer rolls 8 and 9. The wringer roll 9 is adjustable vertically in the frame portions 2 by manipulating the wing nuts 10 that cooperate with the threaded members 11 the ends of which are secured to the movable journal blocks to raise and lower the same.

Mounted on the upper roll 9 is a sheet metal bracket 12 of arcuate shape comprising two portions of the same form and dimensions which are joined at their flange portions 13 by rivets 14 or in any other suitable manner, to a pair of straps 15. The guard 12 may be formed of one piece if desired in which case the flange 13 would be eliminated as this has nothing to do with the function of the device. The guard member 12 at its free ends is shaped in the manner shown in Figs. 2, 3 and 4 to provide a flange element or stripper 16 that is adapted to engage the face of the wringer roll 9. The flange 16 is bent at an angle from the straight portion 17 that diverges from the arcuate portion of the guard and the forms illustrated in the several figures are designed to produce a spring action to exert a yielding

pressure against the contacting faces of the roll and the contacting flanges of the guard.

The ends of the guard are provided with upstruck portions 18 to which are secured 5 rolls 19 the latter being journalled for rotation by pins 20 that are secured to the upstruck portion 18. In Fig. 3 two of such rolls are provided for a purpose as will be hereinafter explained, and in Fig. 4 the portions

10 of the guard contacting with the rolls are shaped to constitute strippers that engage the roll nearer the bite of the rolls than the corresponding element in the type of guard shown in Figs. 2 and 3. The purpose 15 of the construction and function of the guard is otherwise the same.

The guard members 12 are assembled on the upper wringer roll 9 by joining them at their flanges 13. The flanges are secured by 20 a thumb screw 2, or in any other suitable manner to constitute the sections 12 a unitary member.

When the guard is assembled, the flanges 16 will abut the roll 9 exerting a yielding 25 pressure thereon. The pressure on the flanges 16 will cause the entire guard 12 to rotate in the direction of rotation of the wringer roll until one set of guide rolls 19 engage the bottom wringer roll, the guide 30 roll contacting with the bottom wringer roll in accordance with the direction of rotation of the wringer rolls. As shown in Fig. 2 for example, the roll on the right hand side of the vertical center line passing through the 35 rolls contacts with the bottom wringer roll 8 which indicates that the upper roll is rotating in a clockwise direction, this also being true of the illustration shown in Fig. 4. It will be noted that the bottom rolls 19 40 clear the upper wringer roll 9 and the rolls 19 that contact with the upper roll 9 clear the bottom wringer roll 8. With this disposition of the guide rollers 19 the guard may be slightly tilted but for all practical 45 purposes it may be considered as symmetrically disposed with respect to the vertical center line of the wringer rolls.

In Fig. 3 two sets of rolls 19 are employed to secure the guard member in its proper 50 cooperative relation with the wringer rolls, and by the use of double guide rollers the latter may be made to contact with the upper and lower wringer rolls since there is no interference caused by the rotation of 55 the wringer rolls in opposite directions as is the case when but a single group of guide rollers are used.

When clothing is fed to the bite of the

rolls the extended portions of the guard will prevent the operator's hands from getting 60 dangerously near to the roll bite. Thin and delicate fabrics and fabrics of fine texture having a tendency to adhere to the upper wringer roll will be pushed out or peeled off the roll by the strippers 15 which prevent the clothing from being wrapped 65 around the roll.

It is evident from the foregoing description of this invention that wringer roll guards and strippers made in accordance 70 therewith comprise a simple attachment that may readily be placed in its operating position by anyone, and it will also be apparent that the simplicity of the device makes it relatively inexpensive to manufacture and 75 that it is adapted for production in relatively large quantities.

I claim:

1. The combination with a pair of wringer rolls, of a combined guard and stripper 80 detachably mounted on and borne by the rolls and comprising a flexible guard element having offset portions adapted to engage one of the wringer rolls, said guard and stripper being provided with guide members bearing upon the rolls to maintain 85 it in its proper operative position with relation to the rolls.

2. A combined guard and stripper for wringer rolls comprising a flexible member 90 having extending portions adapted to yieldingly engage one of a pair of cooperating roll members, and having a plurality of guide rolls mounted on the guard member to maintain the same in its proper relation 95 with the roll.

3. A combined guard and stripper for wringer rolls comprising a sheet metal member having the extended end portions thereof angularly disposed, and provided with flanges for engaging one of the roll members, said guard being provided with means 100 cooperating with the wringer rolls for maintaining it in its proper cooperative relation with the said wringer rolls.

4. A combined guard and stripper for wringer rolls comprising a sheet metal member having the extended end portions thereof angularly disposed, and being further provided with upstruck portions for securing a plurality of guide rolls that are adapted to contact with the wringer rolls to prevent the guard member from turning with the roll.

In testimony whereof, I sign my name.
GEORGE W. SMITH, JR.
